CLAIM

The ornamental design for a non-axial turbomachine, as shown and described.

DESCRIPTION

FIG. 1 is a perspective view of a non-axial turbomachine showing our new design;

FIG. 2 is a right side elevational view of the non-axial turbomachine of FIG. 1;

FIG. 3 is a left side elevational view of the non-axial turbomachine of FIG. 1;

FIG. 4 is a front side elevational view of the non-axial turbomachine of FIG. 1;

FIG. 5 is a rear side elevational view of the non-axial turbomachine of FIG. 1;

FIG. 6 is a top plan view of the non-axial turbomachine of FIG. 1; and,

FIG. 7 is a bottom plan view of the non-axial turbomachine of FIG. 1.

The broken lines shown in the drawings illustrate portions of the non-axial turbomachine that form no part of the claimed design. The dash dot lines shown in the drawings illustrate boundaries of the claimed design and form no part of the claimed design.
